UNITED STATES PATENT OFFICE.

EUSTACE CREEES AND CHARLES S. COURT, OF PROVIDENCE, RHODE ISLAND,
ASSIGNORS TO THE WATSON & NEWELL COMPANY, INCORPORATED, OF
ATTLEBOROUGH, MASSACHUSETTS.

DESIGN FOR A HANDLE FOR SPOONS.

SPECIFICATION forming part of Design No. 25,936, dated August 18, 1896.

Application filed July 21, 1896. Serial No. 600,065. Term of patent 7 years.

To all whom it may concern:

Be it known that we, EUSTACE CREEES and CHARLES S. COURT, of Providence, in the county of Providence and State of Rhode Island, have invented and produced a new and original Design for Spoons and Similar Articles, of which the following is a specification, reference being had to the accompanying drawing, forming part thereof.

10 The drawing is a representation of a spoon and its handle, illustrating the obverse of our new design, the tine portion of a fork being dotted in position.

The leading features of our design consist in the elongated diverging shell-like ornaments at the lower end of the handle, the double beadings extending from these ornaments and following the outlines of the handle which gradually increases in width toward 15 the upper end, where a lobe-like panel is surmounted by an aggregation of foliated scrolls, the lower end of which laps onto the panel, the lower end of the panel being defined by scrolls and a spray of flowers pendent from 20 the scrolls.

In the drawing, 5 indicates the handle of a spoon or similar article of which 6 is the bowl portion. It may, however, represent the main portion of any similar article to which 25 the handle is adapted to be attached, one of which is indicated in dotted lines.

The outline of the handle, commencing at

its lower end, spreads outward from 7 7 to form the outwardly-turned ends of the shell-like ornaments. It then curves inward and gradually upward to 8 8, where it is broken by groups of short curves, by which the width of the handle is contracted to 9 9. Thence the outline extends upward in long flowing curves, increasing the width of the handle to 40 10 10. From these points it curves slightly inward, and then by a succession of irregular curves finishes the upper end of the handle.

The surface ornamentation comprises the elongated shell-like ornaments 11 11 at the 45 lower end of the handle, finished by the foliated scrolls 12 12 at their upper ends, the double-bead borders 13 13, which follow the outline of the handle to the group scrolls and shell-like foliations 14 at its upper end, being 50 overlapped by leaves 15 and 16 toward the upper part and embracing the panel 17, the scrolls 18, and the foliations 19 pendent from the scrolls.

What we claim is—

The design for handles of spoons and similar articles as herein shown and described.

In witness whereof we have hereunto set our hands.

EUSTACE CREEES.
CHAS. S. COURT.
